COLLAPSIBLE STEREOSCOPE

Frank E. Dasch, Indianapolis, Ind.

Application June 16, 1952, Serial No. 293,727

8 Claims. (Cl. 88—29)

1

This invention relates to a collapsible optical device, especially a stereoscope, which can be packaged in a flat envelope and which can be readily erected and assembled with little skill. The device is especially adapted to be used as a premium or toy to be distributed to children, and its flat packaging permits it to be readily mailed.

In accordance with the invention, a stereoscope has a suitably formed casing blank which may be bent around and interlocked with the internal structure upon assembly, and internal structure comprising a plurality of walls hinged to opposite side plates or spacers one of which may be the casing blank. The walls are provided with aligned apertures and at least one wall carries a pair of lenses. The parts are provided with slots or other supports which in assembled position form a holder to receive a replaceable slide containing a pair of pictures or transparencies to be viewed. When collapsed, the walls and side plates lie flat against each other and against the housing member, and may be secured to a flat support for insertion in a flat envelope. The walls, plates, and housing may be made of cardboard or other suitable stiff sheet material.

The accompanying drawings illustrate the invention. In such drawings, Fig. 1 is a top plan view of a stereoscope in collapsed condition and mounted on a flat support; Fig. 2 is a bottom plan view of the assembly shown in Fig. 1, with parts of the support broken away; Fig. 3 is an isometric view of the assembled stereoscope with a slide in place; Fig. 4 is an isometric view of a slide suitable for use with the stereoscope; Fig. 5 is an isometric view of a partly assembled stereoscope in inverted position; Fig. 6 is an isometric view of the inverted stereoscope in collapsed position; and Fig. 7 is a longitudinal section and Fig. 8 an isometric view of the assembled stereoscope in inverted position.

As shown in the drawings, the stereoscope comprises a casing member 10 of stiff sheet material, such as cardboard, having a straight central portion 12, curved intermediate portions 14 which are scored internally to facilitate bending, and straight end portions 16. Adjacent the front edge of the center portion 12 there is a long narrow slot 18, and in each end edge there is a short notch 20, for cooperation with the slide as will appear. In each end portion 16 a curved cut line provides an inwardly projecting tab 22, and such tabs are used both for securing the collapsed assembly to a mailing support 24, by interengagement with punched openings 26 in the support 24, and for interlocking the stereoscope in erected position, as will appear.

2

The internal structure of the stereoscope, best seen in Figs. 5 and 7, may be made of separate pieces. Preferably, however, and as shown, it is made from a single blank of stiff sheet material, such as cardboard, cut and scored to provide a series of parts separated by scored fold lines and in the following order: a connecting plate or spacer 28, a rear wall 30, a base plate or spacer 32, a front wall 34, a spacing plate 36, an intermediate wall 38, and a tab 40.

In erected assembly, the three walls 30, 34, and 38 stand substantially at right angles to the plates 28 and 32 in spaced parallel relationship with each other. The spacing plate 36 is glued or otherwise secured to the connecting plate 28 adjacent its front edge, and the tab 40 is glued or otherwise secured to the base plate 32. This assembly is secured to the casing 10 with the base plate 32 lying against the center portion 12 and glued or otherwise secured thereto. The wall 34 is aligned with the front edge of the slot 18, and the base plate 32 is provided with a corresponding slot to pass a slide 50 into position against the back face of the front wall 34. At the opposite edge of the front wall 34, the spacing plate 36 and its overlying connecting plate 28 may be provided with a short slot 42 to pass an aligning tab 52 on the slide 50.

The rear wall 30 has a pair of spaced circular openings to the edges of which are glued or otherwise secured a pair of lenses 44, conveniently made of molded transparent plastic material. The ends of the wall 30 project beyond the side edges of the plates 28 and 32 and are rounded. The intermediate wall 38 has a pair of apertures 39, conveniently rectangular in shape, aligned with the lenses 44. Its ends likewise project beyond the edges of the plates and are similarly rounded. The front wall 34 also has a pair of apertures 35, conveniently of rectangular shape, aligned with the apertures 39 and the lenses 44. The three walls 30, 38, and 34 are progressively longer from the rear to the front, and the plates 42 and 28 are similarly wider at the front than at the rear. The connecting plate 28 has a pair of slots 29 near its center and generally parallel with its diverging side edges, to interengage the tabs 22 when the casing is assembled around the internal structure.

In the collapsed position of the internal assembly, the three walls 30, 38, and 34 are bent forwardly about their bottom hinge connections to a position where they lie flat against each other and against the base plate 32 and its underlying central portion 12 of the casing 10. With the internal structure in erected position on the

center portion 12 of the casing 10, the end portions 14 and 16 of the casing are bent around the curved ends of the walls to bring the ends 16 of the casing into overlying relationship against the connecting plate 28, and the tabs 22 are inserted in the slots 29, to hold the casing in assembled position. When this is done, the slots 20 in the end edges of the casing come together in alignment with the short slot 42 at the front of the glued-together connecting plate 28 and 10 spacing plate 36.

In the manufacture of the stereoscope, the blank for the internal structure may be folded through 180° on the fold line between the front wall 34 and the spacing plate 36 and on the fold line between the rear wall 44 and the base plate 32. This will bring the spacing plate 36 into proper registry with the front edge portion of the connecting plate 28, and properly position the tab 40 against the base plate 32, and these parts may be glued to the plates in this position. With the parts in this collapsed position, the lenses 44 may be glued to the edges of the openings in the rear wall 30, or otherwise secured in such openings, as by means of lugs formed on molded lenses. The collapsed internal structure may then be glued to the casing 10, and the whole assembly secured to the mailing support 24 by engagement of the tabs 22 with the openings 26 in that support.

For use, the assembly is detached from the mailing support 24, the internal structure is moved to erect position, with the walls hinging about their connections to the two plates 28 and 32, and the end portions of the casing are wrapped around the erected walls and locked in place by inter-engagement of the tabs 22 with the slots 29. The assembled stereoscope is then turned to upright position, with the center portion 12 of the casing uppermost, and the device is then ready to receive a slide 50 to be viewed.

The slide 50 consists of two layers of material, such as cardboard, provided with aligned apertures positioned to lie in alignment with the apertures of the stereoscope walls, and such two layers are glued together with transparencies 54 accurately positioned in the apertures between the two wall layers. The slide 50 is of a size to be received through the slot 18 in the casing portion 12—which is now the top wall of the stereoscope. The slide is desirably provided with a bottom tab 52 to enter the slot 42 and between the notches 20, to help locate the slide in proper position and focus. The slide desirably also has a top tab 56 by which it may be manipulated into and out of the holder formed by the slots 18 and 42. The slide is viewed by looking through the lenses with the stereoscope held toward the light.

The stereoscope is especially suited for distribution as a premium and for use as a toy by children. It is quite inexpensive to make, and its distribution is facilitated by the fact that it collapses and may be packed in a flat envelope. When erected for use, the parts move into accurately aligned positions, and the device gives a good three-dimensional view of the slides.

I claim as my invention:

1. A collapsible stereoscope comprising three walls hinged at opposite edges to spaced plates and having rounded end portions projecting beyond said plates, a casing secured to one plate and having portions adapted to be wrapped around the plates and the ends of the walls and

overlapping one of said plates, and means to secure the casing in place, said walls being provided with openings arranged in two spaced aligned series, lenses in the openings of one of said walls, said plate and casing members having slots to form a slide-holder in a plane parallel with said lens-containing wall and spaced therefrom.

2. A stereoscope, comprising a casing member, a plurality of walls supported at their edges for pivotal movement about parallel hinge-lines spaced transversely of said casing member, said walls having projecting ends and being progressively larger from the rear wall to the front wall, means interconnecting the opposite edges of said walls and movable to carry them to erect position in spaced parallel relation normal to said casing member, said casing member having portions scored on progressively diverging score lines and adapted to be wrapped about said erect walls, interengaging means to hold said walls erect and said casing in wrapped position in rigid assembly, lenses in the openings of one of said walls, and slide-holder means to receive a slide in spaced alignment with said lenses.

3. A stereoscope, comprising a casing member, a plurality of walls having projecting curved ends and supported at their edges for pivotal movement about spaced parallel hinge lines, means interconnecting the opposite edges of said walls, said walls being movable between a collapsed position flat against said casing member and an erect spaced parallel position normal to said casing member, said casing being adapted to wrap around the curved ends of the erect walls, means to interlock the erect walls and the wrapped casing in rigid assembly, openings in said walls, lenses in the openings in one wall, and slide holder means to support a slide in spaced alignment with said lenses.

4. An optical toy adapted to be distributed in collapsed condition and erected with little skill, comprising a casing blank, a plurality of hinged walls carried by and folded flat against said blank, a spacer interconnecting the free edges of said walls, and movable therewith to hold them in spaced parallel position upon erection thereof, end portions on said blank adapted to be wrapped around the ends of said walls and overlap said spacer to form a casing, interlocking means between said blank portions and said spacer to relatively position said walls and lock the blank in encasing position, said walls having openings positioned to lie in spaced alignment on erection of said walls, and a lens in each opening of an outer wall.

5. An optical toy as defined in claim 4 with the addition of a supporting board and means thereon to engage the blank-carried interlocking means to support the toy in collapsed position on said board for distribution.

6. A collapsible optical toy, comprising a cardboard wall blank cut and scored on spaced fold lines to form a series of alternate walls and wall-spacers with the walls projecting beyond the edges of the spacers and having rounded ends, said blank being foldable to position the walls in spaced parallel relation, and a casing blank having a portion adapted to overlie a spacer and having scored portions adjacent thereto adapted to bend about the rounded ends of said walls, said casing and at least one of said spacers having interengaging tabs and slots cut therein and adapted to interlock said casing with said wall blank, said walls being provided with openings to

lie in spaced alinement and lenses supported in at least some of said openings.

7. A collapsible optical toy, comprising a wall blank scored on spaced fold lines to form a series of three walls with spacers therebetween, said blank being folded to form a wall assembly in which spacers at opposite sides of a group containing two walls lie in overlying relationship, means securing the overlying spacers together in position to locate said two walls in spaced parallel relation when erected normal to one of the spacers, the walls of said blank having openings positioned to be alined when said walls are erect, lenses in at least some of said openings, and a casing blank adapted to be wrapped about said erected wall assembly and secured thereto to lock said assembly in erect position.

8. An optical toy, comprising a casing blank having a center portion and projecting end portions, front and rear walls and at least one intermediate wall hingedly carried by the center portion of the blank on spaced hinge lines extending longitudinally of the blank, said walls having projecting curved ends, the end portions

of the blank being bendable around the curved ends to be supported thereby to form curved side-walls of the toy, the extreme ends of the blank being adapted to come together over the free edges of the walls, means to interlock the casing ends with the walls to hold the casing in assembled position and the walls in erect position, said walls having aligned openings therein, and a lens in each opening of the rear wall.
